UNITED STATES PATENT OFFICE.

WINFIELD S. ROGERS, OF KEENE, NEW HAMPSHIRE.

DESIGN FOR A VEHICLE-BODY.

SPECIFICATION forming part of Design No. 35,951, dated June 10, 1902.

Application filed April 14, 1902. Serial No. 102,940. Term of patent 7 years.

To all whom it may concern:

Be it known that I, WINFIELD S. ROGERS, a citizen of the United States, residing at Keene, in the county of Cheshire and State of New Hampshire, have invented a new and useful Design for a Vehicle-Body, of which the following is a specification, reference being had to the accompanying drawing.

My design relates to a substantially single-seated carriage-body—that is to say, to a carriage-body having a single seating-compartment.

The drawing shows a perspective view of a vehicle-body embodying my design.

My design is characterized principally by a box-like body portion A, having a seating-

compartment near its forward end. The seating-compartment is provided with a forwardly-facing seat B and inwardly-facing side seats C and D.

Having thus fully described my design, what I claim, and desire to secure by Letters Patent of the United States, is—

The design for a vehicle-body substantially as herein shown and described.

In testimony whereof I have hereunto set my hand in the presence of two subscribing witnesses.

WINFIELD S. ROGERS.

Witnesses:

E. J. MARTIN,
ALICE E. GRAVES.
